CLAIM

The ornamental design for a medical device programmer, as shown and described.

DESCRIPTION

FIG. 1 is a top perspective view of a medical device programmer including a programmer base and programmer head;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof;

FIG. 8 is a top perspective view of the programmer base;

FIG. 9 is a top view thereof;

FIG. 10 is a bottom view thereof;

FIG. 11 is a front view thereof;

FIG. 12 is a rear view thereof;

FIG. 13 is a right side view thereof;

FIG. 14 is a left side view thereof;

FIG. 15 is a top perspective view of the programmer head;

FIG. 16 is a top view thereof;

FIG. 17 is a bottom view thereof;

FIG. 18 is a front view thereof;

FIG. 19 is a rear view thereof;

FIG. 20 is a right side view thereof;

FIG. 21 is a left side view thereof; and,

FIG. 22 is a top perspective view of the medical device programmer in an alternative configuration.

The broken lines immediately adjacent to the shaded areas represent the boundaries of the claim, and all other broken lines represent the environment; the broken lines form no part of the claimed design.

1 Claim, 22 Drawing Sheets
